(57) **CLAIM**

The ornamental design for a lectern, as shown and described.

DESCRIPTION

FIG. 1 is a top front perspective view of a lectern according to the present invention.

FIG. 2 is a bottom front perspective view of the lectern of FIG. 1.

FIG. 3 is a top rear perspective view of the lectern of FIG. 1.

FIG. 4 is a top view of the lectern of FIG. 1.

FIG. 5 is a bottom view of the lectern of FIG. 1.

FIG. 6 is a left side view of the lectern of FIG. 1.

FIG. 7 is a right side view of the lectern of FIG. 1.

FIG. 8 is a front view of the lectern of FIG. 1.

FIG. 9 is a rear view of the lectern of FIG. 1.

FIG. 10 is a top front perspective view of another embodiment of a lectern according to the present invention.

FIG. 11 is a bottom front perspective view of the lectern of FIG. 10.

FIG. 12 is a top rear perspective view of the lectern of FIG. 10.

FIG. 13 is a top view of the lectern of FIG. 10.

FIG. 14 is a bottom view of the lectern of FIG. 10.

FIG. 15 is a left side view of the lectern of FIG. 10.

FIG. 16 is a right side view of the lectern of FIG. 10.

FIG. 17 is a front view of the lectern of FIG. 10; and, FIG. 18 is a rear view of the lectern of FIG. 10.

The portions of the drawings appearing in broken lines are for environment only and do not form a part of the claimed design.

1 Claim, 16 Drawing Sheets
